FURNACE AND THE LIKE

Filed May 1, 1926

UNITED STATES PATENT OFFICE

ROGER D. DE WOLF, OF ROCHESTER, NEW YORK

FURNACE AND THE LIKE

Application filed May 1, 1926. Serial No. 106,123.

This invention relates to structures enclosing heat chambers, such as to combustion chamber constructions and furnaces, and particularly to the variety adapted for the burning of finely divided fuel, such as powdered or pulverized coal for example. In the burning of such fuel, the fuel and some or all of the air may be introduced together into the combustion chamber, and since the velocity of the entering air and fuel must of necessity be greater than the rate of flame propagation in order to prevent back fire, a relatively long flame travel is required. There have been operating objections to having the flame travel extended horizontally, and in obtaining a vertical flame travel of sufficient length, difficulty has been experienced in obtaining a sufficiently strong and durable construction, owing to the fact that the heat resisting lining bricks usually employed were incapable of withstanding the pressure from superposed bricks in the high wall necessarily provided when obtaining a flame travel of sufficient length.

The lining bricks burn out or become injured at times, requiring their replacement. Heretofore it has been difficult, and frequently impossible to remove defective or burned lining bricks independently of the others, or without tearing down and then rebuilding the lining walls. When some of the lower bricks were removed there was then no support for the upper bricks which were supported thereon.

An object of the invention is to provide a structure enclosing a heat chamber, such as a furnace, of an improved and more efficient type of construction, particularly as regards the side wall structure, characterized generally by increased strength, with economy of materials and decreased stresses upon the weaker parts. Another object is the provision of such construction in a form facilitating replacement of burned or defective parts with a minimum expenditure of time and expense. More particularly stated, another object is to provide a side wall construction in the nature of a steel frame on which the refractory material or fire bricks are detachably supported for practically independent

removal and by which the principal stresses are carried, so as to afford a construction which may be made of any desired height without danger of injury to or crushing of the lining bricks.

Various other objects and advantages will be apparent from the following description of an embodiment of the invention, and the novel features will be particularly pointed out in connection with the appended claims.

This application is a continuation in part of my copending application, Serial No. 694,196, filed February 21, 1924, which has now matured into Patent No. 1,705,965, issued March 19, 1929.

In the accompanying drawings:

Fig. 1 is an elevation of a part of the front wall of the furnace, with the outer covering removed, and with certain parts of the lining broken away to show other details;

Fig. 2 is a plan of the same section of wall;

Fig. 3 is a sectional elevation through a part of one of the walls of the furnace, and illustrating certain details of construction; and

Fig. 4 is a perspective of a portion of the front wall of the furnace, and illustrating certain details of construction.

Referring now particularly to Figures 2, 3, and 4, the lateral walls of the structure which enclose the combustion chamber include a structural steel frame work having I-beams or posts 10 running vertically. A plurality of hanger blocks 11 are arranged in columns along the vertically extending beams 10 and are anchored thereto in columns in any suitable manner, such as by individual clamping devices 12 which embrace and are clamped to the beam and also portions of each hanger block, as shown in Figures 2 and 3. The blocks may have grooves or undercut portions 13 into which arms of the clamping devices 12 engage, so as to effect a very firm clamping connection between the hanger blocks and the riser beams 10.

Each hanger block is provided at its end opposite the clamp with lateral wings 14, and the wings of each column of hanger blocks extend toward the adjacent blocks of adjacent columns as will be evident from Figures 2 and 4. A plurality of heat resisting

lining bricks 15 are interposed between the columns of hanger blocks and interlocked with the wings 14 so as to be confined through the hanger blocks to the frame. The lining bricks 15 may be made of such dimensions as to extend halfway the distance between two adjacent columns, and thus each double column of bricks between each pair of columns of hanger blocks will fill the space between two columns. Each brick may have on the side edge a vertically extending groove 16 in which a wing 14 of a hanger block may be received.

As will be evident from Figures 2 and 4, whenever two lining bricks 15 are in position between the two columns and are dropped over the wings 14 of the two columns, the bricks will abut one another and thus be locked to the hanger blocks against horizontal displacement. The bricks 15 each extend partially over the projecting end faces of the hanger blocks with which they interlock, and each brick by such extension abuts against the extension of the brick which interlocks with the other wing of the same hanger block, so that the bricks 15 will form a continuous lining for the structure and cover and protect the hanger blocks.

The lining bricks 15 are made of suitable heat resisting material such as fire clay. To reduce the stresses to which such refractory material is subjected, I have provided means for supporting the lining bricks and hanger blocks in groups, and the weight to which any block or lining brick will be subjected will not surpass the weight of any superposed blocks or bricks in that group. I may secure a plurality of angular foot plates or shelves 17 to the steel frame, such as to the vertically extending beams, so as to form ledges. These angular foot plates extend around the interior of the frame at different levels and the hanger blocks 11 rest in groups upon these foot plates so as to be supported thereby from the frame. Thus the hanger blocks 11 will be supported in short columns between the vertically spaced foot plates or shelves.

Certain hanger blocks 11 which are designated 11^a are somewhat longer horizontally than the other blocks, so as to extend slightly further into the combustion chamber, as shown clearly in Fig. 3. These special blocks 11^a are disposed lowermost in each column that rests upon a foot plate or shelf and by reason of their greater lengths there will be a short ledge or shoulder at the forward end of each upon which may rest the lining bricks 15 that are interconnected to the other hanger blocks 11 in that column between foot plates. The lining bricks 15 which are interlocked with the special long hanger blocks 11^a are designated as 15^a and are made somewhat smaller in their dimensions between grooves 16 and the faces which form a part of the chamber wall, so that when assembled

as shown in Figures 3 and 4 the lining bricks 15 and 15^a will form a practically continuous and unbroken lining surface. The lining bricks 15^a are supported against vertical movement upon the lining bricks 15 of the column next below, as will be observed from Figure 3.

It is well known that such a structure will expand and contract with changes in temperature, and unless provision is made for such expansions and contractions, the hanger blocks and lining bricks might be subjected to undesired crushing forces in addition to the weights to be supported. By having the blocks and bricks supported from the frame at intervals on the angular foot plates, they may expand and contract somewhat independently as well as with the frame. The distance between vertically spaced foot plates 17 will be slightly greater than the combined heights of the column of hanger blocks to be interposed therebetween, so that each short column between foot plates may expand between the foot plates without increasing the crushing forces to which the blocks and bricks of that column are subjected.

The lining bricks 15^a which fit against the lowermost block of each column between foot plates will overlie the edge of the foot plate and the space between the foot plate and the hanger block next below it, and thus will protect the foot plate against the heat from the combustion chamber. The bricks 15^a also terminate slightly below the lowermost brick 15 which rests upon the ledge of the hanger block 11^a to which these bricks 15^a are interlocked, so that the columns of interlocked lining bricks which are supported upon each projecting hanger block 11^a may of their own accord expand and contract vertically to a slight extent, and thus accommodate themselves to changes in temperature without varying the compression forces to which they are subjected. The spaces between the superposed columns of hanger blocks and between the superposed columns of lining bricks, may be relatively small since there is only a slight difference in the rates of expansion in the steel frame and the masonry materials of which the hanger blocks and lining bricks are formed.

The slight cracks between the lining bricks 15 and the other bricks 15 just above it which are provided in order to permit of the expansion of the bricks as units will fill with dust which effectively closes them, if desired, and preferably, these cracks or spaces may be filled with a suitable compressible packing which is also heat resisting such as some of the various flaked asbestos packings. Such packing may also be provided if desired in the spaces below each projecting hanger block 11^a and the uppermost hanger block 11 in the column immediately below it.

This packing 15^b is shown clearly in Figure 3.

Each projecting hanger block 11^a this supports the other hanger blocks in the same column between it and the foot plate directly above it, and also the lining bricks 15 and 15^a which are connected to the hanger blocks above it in the same column and also overhanging the projecting block of the column next above. Regardless of the height of the 10 walls the pressure on the hanger blocks and lining bricks will not vary and such blocks and bricks may expand to a limited extent independently of the frame. With such a construction, therefore, the combustion chamber 15 may be of such a vertical height as to provide the desired flame travel.

By referring particularly to Figures 2 to 4, it will be observed that the hanger blocks are individually clamped to the I-beams or 20 posts, and that the lining bricks are attached to the hanger blocks. Therefore, when it is desired to remove and replace defective or burned lining bricks, it is not necessary to entirely tear down the walls.

25 One may merely release the clamping devices for one or more of the hanger blocks by which the lining bricks are held in place and thus a few of the lining bricks may be released to permit of their removal with one or more of 30 the hanger blocks, the other hanger blocks and the lining bricks being separately supported in such a manner as to permit of such removal. At most, only the particular lining bricks of a column supported upon any 35 shoulder or special hanger block 11^a would have to be removed in order to replace any lining brick in that column or group since all of the groups of blocks and bricks are independently supported upon the frame posts 40 and would not be affected by the removal of any of the bricks in any other group. From this it will be observed that little effort and small expense are required in order to renew any portion of the lining as needed.

45 Where the structure is utilized with a boiler, various water tubes may be placed within the chamber and along its lateral walls, and groups of such tubes in connection with drums or reservoirs may be placed in

50 a structure or casing which is connected to the upper end of the combustion chamber at a point spaced from the fuel inlet so as to receive the hot gases of combustion. It will be observed that with this particular block 55 construction utilized in the lateral walls, it is a relatively simple matter to pass tubes through the lateral walls for connection to the water tubes that extend along the sides of the combustion chamber.

60 The tubes along the side walls of the combustion chamber reduce the furnace temperature and thus aid in cooling the walls of the combustion chamber but also provide additional heat interchanging surface subject to the action of the burning fuel.

The structure frame may be enclosed within a suitable sheet covering 19 which is spaced from the hanger blocks and lining bricks so as to form within the structure walls a plurality of vertically extending 70 channels that are divided by the riser I-beams 10 of the frame and the hanger blocks into separate channels 20. The channels thus formed open into the interior of the combustion chamber through apertures 22 in the fire brick lining. The heated air in the various channels 20 will thus be conducted into the combustion chamber through the apertures 22.

In the front wall of the structure it is desirable to prevent direct radiation of the heat from the combustion chamber through the apertures 22 to the outer covering 19, and therefore the hanger blocks may also be provided with shoulders 31, (for instance, see Figures 2, 3 and 4), within the portions of the blocks which are supported upon the foot plates 17. Baffle blocks 32 of heat resisting material are disposed between the columns of hanger blocks so as to fit against the shoulders 31, and such baffle blocks will be in spaced relation to the inner or channel faces of the lining bricks 15 and 15^a. The baffle blocks 32 are disposed opposite the apertures 22 so as to prevent direct radiation from the combustion chamber through the apertures to the outer covering 19, and may be spaced apart vertically by spacing bricks 33 of fire resisting material, the lengths of the spacing bricks being such as to properly space the baffle blocks the desired amount, and leave spaces between the blocks through which the air from the channels may pass to reach the apertures 22. The spacing bricks and baffle blocks may be confined against the shoulders 31 in any suitable manner, such as by bars 34 which extend in directions lengthwise of the channels and bridge a number of the blocks. The bars 34 may be confined against the blocks 32 and bricks 33 by cross bars 35 which are sprung between the devices 12 attached to the beams 10 at the sides of that channel 20.

It will be obvious that various changes in the details, which have been herein described and illustrated in order to explain the nature of invention, may be made by those skilled in the art within the principle and scope of the invention as expressed in the appended claims.

I claim as my invention:

1. In a furnace, a frame enclosing a chamber, hanger blocks arranged in superposed relation along the walls of said frame to form horizontally spaced columns, means carried by said frame for supporting the blocks of each column in groups at different levels, whereby the crushing force on the blocks of each group will not exceed the combined weight of the blocks of that column group,

and heat resisting bricks interlocked with said hanger blocks and forming a continuous lining for the chamber, said bricks being also supported in groups by said hanger blocks whereby the crushing forces on said bricks will not be greater than the combined weight of the bricks of any groups which are in superposed relation.

2. In a furnace, an enclosing structure, the side walls of such structure including an upstanding frame provided with posts, foot plates extending transversely of said posts and secured thereto at different elevations, hanger blocks attached to said posts in superposed relation to one another, and arranged in column groups resting upon and supported by said foot plates, and heat resisting bricks interlocked with the columns of hanger blocks so as to be confined in superposed relation as a continuous lining for the structure wall.

3. In a furnace, an enclosing structure the side walls of such structure including an upstanding frame provided with posts, foot plates extending transversely of said posts and secured thereto at different elevations, hanger blocks attached to said posts in superposed relation to one another, and arranged in column groups resting upon and supported by said foot plates, heat resisting bricks interlocked with the columns of hanger blocks so as to be confined in superposed relation as a continuous lining for the structure wall, the lining bricks of each column being supported in groups through said groups of hanger blocks and said foot plates, as horizontally spaced columns of hanger blocks with lining blocks interconnected therewith.

4. In a furnace, an enclosing structure, the side walls of such structure including an upstanding frame provided with posts, foot plates extending transversely of said posts and secured thereto at different elevations, hanger blocks attached to said posts in superposed relation to one another, and arranged in column groups resting upon and supported by said foot plates, heat resisting bricks interlocked with the columns of hanger blocks so as to be confined in superposed relation as a continuous lining for the structure wall, the upper hanger block of each column group being normally slightly spaced below the foot plate of the group next above it, so as to permit of independent vertical expansion of each column group of hanger blocks.

5. In a furnace, an enclosing structure, the side walls of such structure including an upstanding frame provided with posts, foot plates extending transversely of said posts and secured thereto at different elevations, hanger blocks attached to said posts in superposed relation to one another, and arranged in column groups resting upon and supported by said foot plates, heat resisting bricks inter-

locked with the columns of hanger blocks so as to be confined in superposed relation as a continuous lining for the structure wall, the upper hanger block of each column group being normally slightly spaced below the foot plate of the group next above it, so as to permit of independent vertical expansion of each column group of hanger blocks, the lowermost block of each column group extending slightly further into the enclosure than the others to provide a supporting ledge upon which rest the lining bricks connected to that group.

6. In a furnace, an enclosing structure, the side walls of such structure including an upstanding frame provided with posts, foot plates extending transversely of said posts and secured thereto at different elevations, hanger blocks attached to said posts in superposed relation to one another, and arranged in column groups resting upon and supporting by said foot plates, heat resisting bricks interlocked with the columns of hanger blocks so as to be confined in superposed relation as a continuous lining for the structure wall, the upper hanger block of each column group being normally slightly spaced below the foot plate of the group next above it, so as to permit of independent vertical expansion of each column group of hanger blocks, the lowermost block of each column group extending slightly further into the enclosure than the others to provide a supporting ledge upon which rest the lining bricks connected to that column group, the uppermost lining brick of each group overlapping with the lowermost block of the column group next above, whereby the lining bricks carried by each projecting hanger block will overrun the space between the upper block of that column and the foot plate and form a closed lining.

7. In a furnace, a frame, a plurality of shelves projecting from the inner face of said frame in vertically spaced relation above one another, hanger blocks attached to said frame and arranged in groups forming columns between said shelves, which columns are spaced apart horizontally, at least one block of each column group projecting slightly further from the frame than the others so as to form a supporting ledge, and heat resisting lining bricks attached to said hanger blocks so as to connect the columns of the same and form a continuous lining, said lining bricks being also arranged in columns resting upon the projecting ledges, the bricks between each pair of column blocks overlapping the blocks of the columns next above.

8. In a furnace, a frame, a plurality of shelves projecting from the inner face of said frame in vertically spaced relation above one another, hanger blocks attached to said frame and arranged in groups forming columns between said shelves, which columns

- are spaced apart horizontally, at least one block of each column group projecting slightly further from the frame than the others so as to form a supporting ledge, and heat resisting lining bricks attached to said hanger blocks so as to connect the columns of the same and form a continuous lining, said lining bricks being also arranged in columns resting upon the projecting ledges, the bricks between each pair of column blocks overlapping the blocks of the columns next above, the uppermost lining brick of each column terminating slightly below the lowermost brick of the column immediately above, whereby said lining bricks may expand vertically between the column groups, and whereby the lining bricks and hanger blocks will be supported in groups upon the foot plates.
9. In a furnace, a frame having ledges upon its inner face at different elevations, anchor blocks attached to the frame and arranged in columns between said ledges, with each column supported upon a ledge, at least one block of each column projecting slightly further than the others to form an abutment, lining bricks filling the spaces between the columns of blocks in order to form a continuous lining surface, said bricks being arranged in superposed groups, resting upon the projecting abutments of the blocks, the bricks supported by one abutment of each group of blocks overlapping the ledge next above, and also a block of the column next above, in order to cover and protect the frame ledges and to limit the crushing force upon the blocks and bricks to the weight of the groups carried thereby independently of the height of the frame.
10. In a furnace, a frame having ledges upon its inner faces at different elevations, anchor blocks attached to the frame and arranged in columns between said ledges, with each column supported upon a ledge, at least one block of each column projecting slightly further than the others to form an abutment, lining bricks filling the spaces between the columns of blocks in order to form a continuous lining surface, said bricks being arranged in superposed groups, resting upon the projecting abutments of the blocks, the bricks supported by one abutment of each group of blocks overlapping the ledge next above, and also a block of the column next above, in order to cover and protect the frame ledges and to limit the crushing force upon the blocks and bricks to the weight of the groups carried thereby independently of the height of the frame.
11. In a furnace, a frame having ledges upon its inner face at different elevations, anchor blocks attached to the frame and arranged in columns between said ledges, with each column supported upon a ledge, at least one block of each column projecting slightly further than the others to form an abutment, lining bricks filling the spaces between the columns of blocks in order to form a continuous lining surface, said bricks being arranged in superposed groups, resting upon the projecting abutments of the blocks, the bricks supported by one abutment of each group of blocks overlapping the ledge next above, and also a block of the column next above, in order to cover and protect the frame ledges and to limit the crushing force upon the blocks and bricks to the weight of the groups carried thereby independently of the height of the frame, the said bricks which overlap the lowermost blocks of each column being slightly spaced from the bricks of the group immediately above it, whereby said bricks may expand vertically to a limited extent without varying the crushing forces upon the bricks, each column of blocks being slightly shorter than the space between the ledges, whereby each column of blocks may expand vertically somewhat without varying the crushing force upon them.
12. In a furnace, a frame having ledges upon its inner face at different elevations, anchor blocks attached to the frame and arranged in columns between said ledges, with each column supported upon a ledge, at least one block of each column projecting slightly further than the others to form an abutment, lining bricks filling the spaces between the columns of blocks in order to form a continuous lining surface, said bricks being arranged in superposed groups, resting upon the projecting abutments of the blocks, the bricks supported by one abutment of each group of blocks overlapping the ledge next above and along a block of the column next above in order to cover and protect the frame ledges and to limit the crushing force upon the blocks and bricks to the weight of the groups carried thereby independently of the height of the frame, the said bricks which overlap the lowermost blocks of each column being slightly spaced from the bricks of the group immediately above it, whereby said bricks may expand vertically to a limited extent without varying the crushing forces upon the bricks, each column of blocks being slightly shorter than the space between the ledges, whereby each column of blocks may expand vertically somewhat without varying the crushing force upon them.
13. In a furnace, a structure enclosing a combustion chamber and having upstanding lateral walls comprising a structural steel frame, hanger blocks anchored to said frame along the inner face thereof, and fire resisting bricks interlocked with said hanger blocks and forming a continuous surface heat resisting lining for the combustion chamber, whereby the lining may be renewed in sections by merely unclamping and removing the hanger blocks which confine the particular lining bricks to be renewed.

14. In a furnace, a structure enclosing a combustion chamber and having upstanding lateral walls comprising a structural steel frame, anchor blocks attached to said frame and supported thereby at points spaced throughout its height, and heat resisting bricks interlocked with and supported by said anchor blocks, so as to form a continuous surface heat resisting lining which is supported from the frame through said anchor blocks. 70
15. In a wall structure, anchoring blocks and means supporting the same in vertically and horizontally spaced relation, and surfacing blocks arranged in stacks and having vertical sliding interlocking engagement with said anchoring blocks and individually removable therefrom by vertical sliding movement to extreme position above the co-operating anchor blocks. 75
16. In a wall structure, a metallic framework including columns and rigidly connected thereto shelf-forming beams, anchoring blocks supported by said shelf-forming beams and anchored to said framework, surfacing blocks having vertical sliding interlocking engagement with said anchoring blocks and removable therefrom one at a time by vertical sliding movement to an extreme position above said anchoring blocks. 80
17. In a wall structure, anchoring blocks and means supporting the same in vertically and horizontally spaced relation, surfacing blocks arranged in stacks and having vertical sliding interlocking engagement with said anchoring blocks and individually removable therefrom by a vertical sliding movement to extreme position above the co-operating anchor blocks, the said anchor blocks and surfacing blocks forming independent belts in the wall, and filler blocks interposed between the belts. 85
18. In a wall structure, a metallic framework including columns and rigidly connected thereto shelf-forming beams, anchoring blocks supported by said shelf-forming beams and anchored to said framework, surfacing blocks having vertical sliding interlocking engagement with said anchoring blocks and removable therefrom one at a time by vertical sliding movement to an extreme position above said anchoring blocks, the said anchor blocks and surfacing blocks forming independent belts in the wall, and filler blocks interposed between the belts. 90
19. In a wall structure, anchoring blocks and means supporting the same in vertically and horizontally spaced relation, surfacing blocks arranged in stacks and having vertical sliding interlocking engagement with said anchoring blocks and individually removable therefrom by vertical sliding movement to extreme position above the co-operating anchor blocks, the said anchor blocks and surfacing blocks forming independent belts 95
20. In a furnace, a structure enclosing a combustion chamber and having upstanding walls comprising a frame, anchor members attached to said frame and supported thereby at points spaced throughout its height, and a plurality of heat resisting bricks supported by said anchor members and forming a heat resisting lining for said combustion chamber, substantially all of said bricks being interlocked with said anchor members. 100
21. In a furnace, a structure enclosing a combustion chamber and having upstanding walls comprising a frame including a series of upwardly extending frame members horizontally spaced from each other, a series of upwardly extending groups of anchor members, each group being secured to one of said frame members so that it may be removed from such frame member independently of other groups, and a plurality of heat resisting bricks interlocked with said anchor members and forming a lining for said combustion chamber. 105
22. In a furnace, a structure enclosing a combustion chamber and having upstanding walls comprising a frame including a series of upwardly extending frame members horizontally spaced from each other, a series of upwardly extending groups of anchor members, one group being arranged adjacent each of said upwardly extending frame members and each group comprising a plurality of superposed anchor members, means securing each of said anchor members individually to its adjacent frame member so that any anchor member may be removed independently of the anchor members of any other group, and a plurality of heat resisting bricks interlocked with said anchor members to form a lining for said combustion chamber. 110
23. In a furnace construction, a series of upwardly extending beams provided with abutments, hanger bricks supported by said abutments, and facing bricks having detachable interlocking engagement with said hanger bricks. 115
24. In a furnace construction, a supporting frame comprising a series of upwardly extending beams provided with abutments, hanger bricks supported by said abutments and secured to said frame, and facing bricks having detachable interlocking engagement with said hanger bricks. 120
